FIG. 1

Louis F. Bogia, Jr.

By
Victor J. Evans
Attorney

UNITED STATES PATENT OFFICE.

LOUIS FRANCIS BOGLIA, JR., OF PHILADELPHIA, PENNSYLVANIA.

CLIP.

SPECIFICATION forming part of Letters Patent No. 711,817, dated October 21, 1902.

Application filed October 18, 1901. Serial No. 79,163. (No model.)

To all whom it may concern:

Be it known that I, LOUIS FRANCIS BOGLIA, Jr., a citizen of the United States, residing at Philadelphia, in the county of Philadelphia and State of Pennsylvania, have invented certain new and useful Improvements in Clips; and I do hereby declare the following to be a full, clear, and exact description of the invention, such as will enable others skilled in the art to which it appertains to make and use the same.

This invention relates to clips, and has for its objects the production of a device of this character adapted to secure against casual disconnection of the contiguous or adjacent parts of an article or articles of wearing-apparel; second, to provide a device of the kind named adapted to be secured to an article of apparel in such manner as to obviate the necessity of attaching and detaching the clip therefrom when removing or replacing the garment; and third, to provide an improved device which may be conveniently utilized as a garment-supporter.

The invention consists in an improved article of manufacture of novel construction hereinafter described and claimed.

I have fully and clearly illustrated my improved device in the accompanying drawings, in which—

Figure 1 is a perspective view of a shoe provided with my improved clip, illustrating one manner in which the same may be utilized. Fig. 2 is a front elevation of the clip. Fig. 3 is a side elevation thereof, and Fig. 4 is a rear elevation. Fig. 5 is a front elevation of a slight modification. Fig. 6 is a side elevation thereof, and Fig. 7 is a rear elevation. Fig. 8 is a view showing the blank extended.

Referring to the drawings, Fig. 8, 1 designates the blank from which the device is constructed, consisting of a single piece of suitable sheet metal formed with an attaching-plate 2, of any suitable contour, from which are stamped fastening-prongs 3, adapted to be projected through the material to which the clip is attached and then turned down to clamp the device in position. As shown at 4, the base-plate and the intermediate portion 1 is bent to form a curve, having its opposite ends elongated so as to extend later-

ally in loop form, whereby the same is adapted to coact with the upper edges of the upper of the shoe. In front of the portion 4^a I form a 55 circular portion 5, having an aperture 6, adapted to take in and engage over the knot of the lacing, and thus hold the tie from becoming loose. From the circular part 5 an extension 7 is made, adapted to have its end 60 turned into a bead or rounded portion 8, as indicated in Fig. 3 of the drawings, so as to provide a smooth edge to prevent abrasion or wear of contacting surfaces. Between the base and intermediate portion and below the 65 curved portion of the loops are interposed the opposite side-lacing edges of the upper of the shoe, so that when the upper edges of the upper are inclosed in the loops the side edges of the same will be inclosed between the 70 space of the base-piece and intermediate piece.

To form the article from the blank described, the part 5, with a portion of the part 4^a, is bent down upon the blank, as indicated in 75 Fig. 3 of the drawings, to form a spring-lip and the fastening-plate bent down on the vertical part 4, substantially as shown in Fig. 3 of the drawings, to form a channel and a vertical part directed upward and bent down on 80 the intermediate portion.

Fig. 1 of the drawings illustrates the manner of attaching my improvement to a shoe. The shoe is of the usual construction, in which 85 9 designates the uppers, secured together by a lace 10, and 11 the tongue thereof. In attaching the clip thereto the former is secured to the tongue 11 by inserting the fastening-prongs 3 therein and bending them back. The adjacent ends of the uppers are received 90 in the extended seat of the clip, thus presenting the spring-lip 5 upon the exterior of the shoe ready to receive the bow of the lace 10, the knot of which fits within the aperture 6, holding said bow against casual disconnection.

In Figs. 5, 6, and 7 I have shown a slight modification of my improved clip, consisting of an attaching-plate 12, substantially the same as the plate 2, and a spring-lip 13. This 100 form of clip is especially adapted for use upon low shoes and as a garment-supporter, and it is attached to an article of wearing-apparel in the same manner as the form shown in Figs.

2, 3, and 4. In order that the clip may not become accidentally detached from an article where the fastening-prong 3 cannot secure a firm hold, I provide the plate 2 with perforations 14 in order to permit the clip to be sewed to an article.

While I have shown the preferred form of my invention, I do not wish to be understood as limiting myself thereto, as I am aware that 10 modifications may be made therein without departing from the principle or sacrificing any of the advantages thereof, and I therefore reserve to myself the right to make such changes as fairly fall within the scope of my invention.

Having thus fully described my invention, what I claim as new, and desire to secure by Letters Patent, is—

A clip for attachment to the tongues of shoes consisting of an attaching base-plate, 20 an intermediate portion located in front of the same and an outwardly-curved portion having a central opening therein located in front of the intermediate portion, said curved portion provided with opposite extended sides, 25 and a curved portion formed at the intersection of the base-plate and intermediate portion having laterally-extended loop ends, substantially as specified.

In testimony whereof I affix my signature 30 in presence of two witnesses.

LOUIS FRANCIS BOGLIA, JR.
